(57) **CLAIM**

The ornamental design for a container to ship sellable inventory, as shown and described.

DESCRIPTION

A portion of the disclosure of this patent document contains material to which a claim for copyright is made. The copyright owner has no objection to the reproduction of the patent document or the patent disclosure, as it appears in the U.S. Patent Office records, but reserves all other copyright rights whatsoever.

FIG. 1 is a first perspective view of a first embodiment of a container, taken from above;

FIG. 2 is a second perspective view of the first embodiment of the container of FIG. 1, taken from below;

FIG. 3 is an expanded view of a portion of the bottom surface of the first embodiment of the container illustrating a texture. The texture illustrated in FIG. 3 applies to the bottom surface of the container, as shown in FIG. 2;

FIG. 4 is a third perspective view of the first embodiment of the container of FIG. 1, taken from above;

FIG. 5 is a top plan view of the first embodiment of the container of FIG. 1;

FIG. 6 is a bottom plan view of the first embodiment thereof;

FIG. 7 is a left-side view of the first embodiment thereof;

FIG. 8 is a right-side view of the first embodiment thereof;

FIG. 9 is a front view of the first embodiment thereof;

FIG. 10 is a back view of the first embodiment thereof;

FIG. 11 is a fourth perspective view of the first embodiment thereof;

FIG. 12 is a fifth perspective view of the first embodiment thereof;

FIG. 13 is a perspective view of a second embodiment of the Container, taken from below. The second embodiment includes illustrations identical to the views illustrated in FIGS. 1, 5, and 7-12 shown above;

FIG. 14 is an enlarged view of a portion of the bottom surface of the second embodiment thereof illustrating texture; and,
